UNITED STATES PATENT OFFICE.

GEORGE H. ZOUCK, OF ORANGE, NEW JERSEY, ASSIGNOR TO AIR REDUCTION COMPANY, INC., A CORPORATION OF NEW YORK.

CUTTING-BLOWPIPE.

1,332,281.

Specification of Letters Patent.

Patented Mar. 2, 1920.

Application filed October 8, 1919. Serial No. 329,225.

To all whom it may concern:

Be it known that I, GEORGE H. ZOUCK, a citizen of the United States, residing at Orange, in the county of Essex, State of New Jersey, have invented certain new and useful Improvements in Cutting-Blowpipes; and I do hereby declare the following to be a full, clear, and exact description of the invention, such as will enable others skilled in the art to which it appertains to make and use the same.

This invention relates to blowpipes burning mixtures of combustible and oxidizing gases and arranged to direct a jet of oxidizing gas upon a selected portion of the work, which is maintained at the ignition temperature by the burning mixture. Such blowpipes are widely used in cutting metals.

In blowpipes of the character described, it is desirable and usual to provide a controlling valve for the cutting jet of oxidizing gas and the primary object of the present invention is the provision of a simple, inexpensive, easily operable and effective actuating means for the cutting jet controlling valve.

A further object of the invention is the provision of an actuating means which holds the valve open during the cutting operation without effort or manipulation by the operator, beyond the simple movement of the actuating means to open the valve, and of an adjustment to take up wear of the parts so that the blowpipe may be maintained in prime working condition for a substantially indefinite period.

These and other objects and advantages of the invention will be apparent as it is better understood by reference to the following specification, when read in connection with the accompanying drawing, illustrating the preferred embodiment of the invention, in which,

Figure 1 is a longitudinal section through a blowpipe constructed in accordance with my invention;

Fig. 2 is a section on the line 2—2 of Fig. 1;

Fig. 3 is a section on the line 3—3 of Fig. 2;

Fig. 4 is a section on the line 4—4 of Fig. 2; and

Fig. 5 is a section on the line 5—5 of Fig. 1.

Referring to the drawing, 5 indicates a blowpipe head adapted to receive an interchangeable tip 6. The head and tip may be of any suitable or well known construction and form no part of the present invention, it being essential merely that the tip provides for one or more heating jets supplied with combustible and oxidizing gases and a cutting jet supplied with an oxidizing gas while the head is constructed to deliver the gases to the tip.

In the present embodiment of my invention, the gases are conveyed to the head through three independent pipes, 7, 8 and 9, the pipe 7 carrying the oxidizing gas for the cutting jet and the pipes 8 and 9 carrying respectively, oxidizing and combustible gases for the heating jets. The pipes 7, 8 and 9 terminate in, and are secured to, a butt 10 in which the controlling valves for the gases are mounted.

The butt 10 is preferably a metal casting which is bored and counterbored to provide a valve chamber 11, having a seat 12 against which a conical valve 13 is normally seated by a spring 14 surrounding a stem 15 of the valve and bearing against a removable plug 16 threaded into the butt 10. The valve chamber 11 is connected by a passage 17 to a nipple 18 to which a hose or other flexible connection may be secured in the well known manner, to deliver oxidizing gas from a source thereof, such as a pressure tank, to the valve chamber. A passage 19 extending from the seat 12 to the pipe 7 permits passage of the oxidizing gas to the pipe when the valve 13 is lifted from the seat.

A stem 20 of the valve 13 is supported in a suitable opening provided therefor, in the butt 10, and is provided with a rounded end 21. A gland 22 prevents escape of the oxidizing gas about the stem which is, nevertheless, permitted to move freely when actuated as hereinafter explained to lift the valve from its seat.

100.

The rearward portions of the pipes 7, 8 and 9 are surrounded by a sleeve 23 which is preferably knurled to provide a handle whereby the blowpipe may be grasped and firmly held by the operator. The sleeve 23 is preferably fastened to the butt 10 and tapered at its forward end as indicated in the drawing to give a finished appearance to the blowpipe. At one side, the sleeve 23 is provided with a longitudinally extending depression 24 and a slide 25 is disposed therein for reciprocal movement, extensions 26 and 27 thereon being disposed respectively in openings provided therefor in a guide block 28 fastened to the sleeve 23 and in the butt 10. A trigger 29 is pivotally mounted at 30 on the slide 25 and has an end 31 disposed in an opening 32 in the sleeve 23. Thus by pulling the trigger 29, the slide 25 may be moved rearwardly with relation to the sleeve or handle 23.

A cam block 33 is adjustably mounted on the rearward end of the slide 25, being preferably secured by a stud 34, disposed in a slot 35 in the slide 25, and threadedly engaged by a nut 35'. A take-up block 36 is supported between a shoulder 37 on the slide 35 and the cam block 33 by a screw 38 which passes through the slide 25 and threadedly 30 engages the take-up block. The cam block and take-up block have co-operating sloping surfaces so that by adjusting the nut 35' and screw 38, the cam block may be securely held in adjusted position.

35 The cam block 33 is provided with a cam face 39 against which rests a thrust arm 40, pivoted at 41 on the butt 10. The opposite side of the arm 40 bears against the rounded end 21 of the stem 20 and when the slide 25 is moved rearwardly, the thrust arm 40 rides over the cam face at the same time the stem 20 is actuated to carry the valve 13 away from its seat thus permitting oxidizing gas to pass into the pipe 7. The movement of the slide 25 is sufficient to carry the cam face beyond the point where the spring 14 will return the slide to its normal position and consequently the valve will remain open until the slide is moved slightly 50 in the opposite direction, whereupon the spring will force the slide forwardly thus permitting the valve to seat.

A passage 42 connects the valve chamber 11 to a valve chamber 43 which is in turn 55 connected by a passage 44 to the pipe 8 conveying oxidizing gas for the heating jet. A needle valve 45 of well known construction, controlled by a head 46, is disposed in the valve chamber 43 to regulate the flow of such gas. A passage 47 in the butt 10 connects a nipple 48 to a valve chamber 49 in which a needle valve 49', similar to the valve 45 and controlled by a head 50, is disposed. The nipple 48 may be connected by a 60 hose or other suitable connection with a

source of combustible gas which is conveyed through a passage 51 from the valve chamber 49 to the pipe 9.

From the foregoing description, it will be apparent that I have perfected a blowpipe construction of marked utility. All of the operating parts are readily accessible and may be observed from time to time for the purpose of ascertaining their condition without separating the sleeve from the butt. Adjustment for wear may also be made without dismounting any of the parts. It will be noted, moreover, that the oxidizing gas for the cutting jet passes through the butt by the most direct route which is a distinct advantage. All of the parts are of sturdy construction and maximum life of the blowpipe is thus assured. If the valve in the oxygen line becomes foul through careless use, it may be quickly removed, 85 cleaned and replaced. Such parts as are subject to wear may be readily renewed with the minimum effort.

Various changes may obviously be made in the form, arrangement and construction 90 of the parts without departing from the spirit and scope of the invention as defined in the accompanying claims.

I claim:

1. In a cutting blowpipe, the combination 95 of a head, pipes for separately conveying oxidizing gas for a cutting jet and oxidizing and combustible gases for a heating jet to said head, a butt to which said pipes are connected, a valve chamber in said butt, a 100 passage in said butt connecting said valve chamber and the cutting jet pipe, a spring actuated valve in said chamber, a sleeve surrounding said pipes, a longitudinally slid- 105 able member outside said sleeve and having an operating connection with said valve, and passages in said butt for delivering oxidizing gas to said chamber and to one of the heating jet pipes independently of said valve and combustible gas to another of said 110 heating jet pipes.

2. In a cutting blowpipe, the combination 115 of a head, pipes for separately conveying oxidizing gas for a cutting jet and oxidizing and combustible gases for a heating jet to said head, a butt to which said pipes are connected, a valve chamber in said butt, a 120 passage in said butt connecting said valve chamber and the cutting jet pipe, a spring actuated valve in said chamber, a sleeve surrounding said pipes, a longitudinally slid- 125 able member outside said sleeve and having an operating connection with said valve, a pivoted trigger for actuating said slide, and passages in said butt for delivering oxidizing gas to said chamber and to one of the heating jet pipes independently of said valve and combustible gas to another of said heating jet pipes.

3. In a cutting blowpipe, the combination 130

of a head, pipes for separately conveying oxidizing gas for a cutting jet and oxidizing and combustible gases for a heating jet to said head, a butt to which said pipes are connected, a valve chamber in said butt, a passage in said butt connecting said valve chamber and the cutting jet pipe, a spring actuated valve in said chamber, a sleeve surrounding said pipes and a longitudinally 5 slide member outside said sleeve and having an operating connection with said valve, passages in said butt for delivering oxidizing gas to said chamber and to one of the heating jet pipes independently of said 10 valve and combustible gas to another of said heating jet pipes, and needle valves controlling the passage of gas to said heating jet pipes.

4. In a cutting blowpipe, the combination of a head, pipes for separately conveying oxidizing gas for a cutting jet and oxidizing and combustible gas for a heating jet to said head, a butt to which said pipes are connected, a valve chamber in said butt, a passage in said butt connecting said chamber and the cutting jet pipe, a spring actuated valve in said chamber, a sleeve surrounding said pipes and forming a handle for the blowpipe, a longitudinally slideable member outside said handle and having an operating connection with said valve, including a cam surface on said member, and passages in said butt for delivering oxidizing gas to said chamber and to one of the heating jet pipes independently of said valve and combustible gas to another of said heating jet pipes.

5. In a cutting blowpipe, the combination of a head, pipes for separately conveying oxidizing gas for a cutting jet and oxidizing and combustible gas for a heating jet to said head, a butt to which said pipes are connected, a valve chamber in said butt, a passage in said butt connecting said valve chamber and the cutting jet pipe, a spring actuated valve in said chamber, a sleeve surrounding said pipes and forming a handle for the blowpipe, a longitudinally slideable member outside said handle and having an operating connection with said valve, including an adjustable cam block on said member, and passages in said butt for delivering oxidizing gas to said chamber and to one of the heating jet pipes independently of said valve and combustible gas to another of said heating jet pipes.

6. In a cutting blowpipe, the combination of a head, pipes for separately conveying oxidizing gas for a cutting jet and oxidizing and combustible gas for a heating jet to said head, a butt to which said pipes are connected, a valve chamber in said butt, a passage in said butt connecting said valve chamber and the cutting jet pipe, a spring actuated valve in said chamber, a sleeve sur-

rounding said pipes and forming a handle for the blowpipe, a longitudinally slideable member outside said handle and having an operating connection with said valve, including a cam surface on said member, a 70 pivoted trigger for actuating said slide, and passages in said butt for delivering oxidizing gas to said chamber and to one of the heating jet pipes independently of said valve and combustible gas to another of said heating 75 jet pipes.

7. In a cutting blowpipe, the combination of a head, pipes for separately conveying oxidizing gas for a cutting jet, and oxidizing and combustible gas for a heating jet to 80 said head, a butt to which said pipes are connected, a sleeve surrounding said pipes adjacent said butt and forming a handle for said blowpipe, a longitudinal depression in said handle, a slide in said depression and 85 arranged externally of said handle, passages in said butt for conveying gases to the heating jet pipes, a passage in said butt for conveying gas to the cutting jet pipe, a valve controlling the last mentioned passage and 90 operating connections between said valve and slide.

8. In a cutting blowpipe, the combination of a head, pipes for separately conveying oxidizing gas for a cutting jet, and oxidizing 95 and combustible gas for a heating jet to said head, a butt to which said pipes are connected, a sleeve surrounding said pipes adjacent said butt and forming a handle for said blowpipe, a longitudinal groove in said 100 handle, a slide in said groove, passages in said butt for conveying gases to the heating jet pipes, a passage in said butt for conveying gas to the cutting jet pipe, a valve controlling the last mentioned passage and 105 operating connections between said valve and slide including a stem on said valve, a cam surface on said slide and an intermediate thrust member between said cam surface and stem.

9. In a cutting blowpipe, the combination of a head, pipes for separately conveying oxidizing gas for a cutting jet, and oxidizing and combustible gas for a heating jet to said head, a butt to which said pipes are connected, a sleeve surrounding said pipes adjacent said butt and forming a handle for said blowpipe, a longitudinal groove in said handle, a slide in said groove, passages in said butt for conveying gases to the heating 120 jet pipes, a passage in said butt for conveying gas to the cutting jet pipe, a valve controlling the last mentioned passage and operating connections between said valve and slide including a stem on said valve, an adjustable cam block on said slide and an intermediate thrust member between said cam block and stem.

10. In a cutting blowpipe, the combination of a head, pipes for separately convey- 130

ing oxidizing gas for a cutting jet, and oxidizing and combustible gas for a heating jet to said head, a butt to which said pipes are connected, a sleeve surrounding said pipes 5 adjacent said butt and forming a handle for said blowpipe, a longitudinal depression in said handle, a slide in said depression, a pivoted trigger for actuating said slide,

passages in said butt for conveying gases to the heating jet pipes, a passage in said butt 10 for conveying gas to the cutting jet pipe, a valve controlling the last mentioned passage and operating connections between said valve and slide.

In testimony whereof I affix my signature. 15
GEORGE H. ZOUCK.
